UNITED STATES PATENT OFFICE

2,541,941

DRY CELL CONTAINER AND LAMP HOLDING
CLIP COMBINED

Frank J. Shenk, New Orleans, La.

Application April 7, 1947, Serial No. 739,744

1 Claim. (Cl. 240—10.6)

1

This invention relates to an accessory-type novelty light, that is, a small electric bulb and current-supplying fixtures for supporting same in an operating position.

Briefly, the invention comprises a pair of wire and contact-equipped fixtures for supporting a miniature light bulb, of appropriate shape, therebetween, the bulb having receptacles at its ends constituting fittings for coaction with contacts on the fixtures, whereby to permit the bulb to be conveniently and detachably mounted between said fixtures.

In keeping with the scope of the inventive concept, the fixtures are provided with current-conducting wires, and said wires are adapted to be electrically connected with a dry cell battery, or, batteries, such as are used in present-day flashlights. It follows that it is an object of the invention to provide a simple, portable assemblage including a pair of complementary fixtures connectible with a flashlight battery or the like, said fixtures being adapted to be fixedly mounted and one fixture including a spring-pressed contact element which exerts sufficient pressure against the adjacent end of the bulb to hold the latter between the fixtures when said bulb is in use.

Another object of the invention is to provide a pair of wire-equipped current-supplying fixtures characterized by semi-spherical contact elements, one fixed and the other being spring-pressed and slidably, whereby to permit the coacting bulb to be snapped in and out of place.

More specifically, another object of the invention is to provide a simple and economical small-sized bulb, for example, about an inch or so long, which is fashioned from an open-ended glass or equivalent tube, said tube having metal caps fitted over its opposite ends and said caps having semi-spherical receptacles, for reception of the semi-spherical convex contact elements, on the opposite ends of the bulb.

Other objects and advantages will become more readily apparent from the following description and the accompanying illustrative drawings.

In the drawings, wherein like numerals are employed to designate like parts throughout the views:

Figure 1 is a perspective view, showing the electric light constructed in accordance with the principles of the invention and employing a curved bulb.

Figure 2 is a central longitudinal sectional view with parts in elevation.

Figures 3 and 4 are transverse or cross-sectional views on the lines 3—3 and 4—4 respect-

2
tively of Figure 2, looking in the direction of the arrows.

Figure 5 is a perspective view of one of the parts of one of the bulb-supporting fixtures.

5 Figure 6 is a perspective view showing a battery holder and clip carried thereby which serves to support the bulb and coating fixtures.

Figure 7 is a transverse section on line 7—7 of Figure 6, looking in the direction of the arrows.

10 Figure 8 is a longitudinal sectional view taken centrally through Figures 6 and 7.

Referring now to the drawings by distinguishing reference numerals, it will be noted that there are several units which go to make up the equipment. That is to say, there is a miniature lamp or bulb 7 and a pair of end-fixtures 8 and 9 between which the bulb is removably held in place. The bulb comprises a glass tube 10 with a filament 11 therein, said filament being attached to end-closing caps 12 and 13, fitted telescopingly over the open ends of the tube. The caps have concaved end-portions 14 and 15 which constitute receptacles and which serve to receive and accommodate the semi-spherical convex contact elements 16 and 17, carried by the fixtures 8 and 9. The fixture 8 comprises a cylindrical plug of insulation or the like having a flange 18 on one end surrounding and retaining the contact element 16 in place. The latter element is joined with the anchored end portion 19 of the current supply wire 20.

The fixture to the right in the drawings, the part 9, comprises a cylindrical cup 21 having a current supply wire 22 attached thereto, which wire is, in turn, connected with a coil spring 23, in a manner to pass the current through the spring. The current is then delivered to a projectible and retractible plunger 24 comprising a disk 25, a stem 26 and the aforementioned semi-spherical convexed contact head 17. The entire plunger 24 is slidable in the cylinder and is pressed outwardly by the influence of the spring. It follows that one contact head 16 fits removably in the receptacle 14 and the other contact head 17 fits in the receptacle 15. Also, in actual practice, the fixtures 8 and 9 are, in some manner, (not shown) rigidly supported. For example, let us say that the structure is to be employed in a pocketbook. Under such circumstances, the

45 two mounts or fixtures 8 and 9 would be secured by clips, not shown, or the like, in the pocketbook at a convenient point. A small battery, not shown, would be attached to the current intake ends of the wires 20 and 22. Thus, by snapping 50 the bulb in place between the contacts 16 and

17, a source of electric light would be provided. A structure of this type is also usable on furniture ornaments and in connection with novelties such as toys, where a source of light is wanted. In all instances, the fixtures 8 and 9 are rigidly applied to the toy or other support and the bulb is inserted and removed, as desired. Of course, a switch (not shown) could be included in the circuit; or, the current could be simply cut off and on by inserting the bulb when needed and removing same when not in use.

I also call attention to the fact that the bulbs may be made of different shapes to conform to objects with which same are to be connected in practice.

The description so far relates merely to the bulb and the special accommodating fixtures serving as receptacles at the end-portions of the bulb as shown in Figures 1 to 5 inclusive. At this point, attention is directed to the holding means shown in Figures 6, 7 and 8. Although this particular holding means is not necessarily an essential phase of the instant case, it has been devised as a component aspect of the disclosure. It will be observed, for example, that a cylinder preferably of curved form is denoted at 21 and this serves as a receptacle for a dry cell battery 28 (see Fig. 8), one end wire 22 being connected to the right hand end of the cylinder for electrical coaction with the adjacent end of the dry cell battery. The opposite end of the cylinder is provided with a closing plug or cap 29 having a contact spring 30 engaging the adjacent end of the dry cell. This end-portion serves to accommodate the remaining wire 20 from the fixture 8. Thus, the wire on the fixture 8 is connected at the left in Figure 8 and the remaining wire 22 at the right. The cylinder is provided on one side with a channel-shaped sheath or clip 31 and this is such that it serves as a receiver and holder for all three parts, that is, 7, 8 and 9. It is evident, therefore, that Figures 6, 7 and 8 exemplify a ways and means whereby the bulb and fixtures may be suitably assembled and held in operative relationship.

Minor changes in shape, size, materials and arrangement of parts may be resorted to in actual practice so long as no departure is made from the invention as claimed.

I claim:

A structure of the class shown and described comprising an elongated dry cell containing cylinder closed at one end and open at its opposite end, a dry cell fitting removably in said cylinder, a removable closure plugged into the open end of said cylinder and provided with a contact spring cooperable with the adjacent end of the dry cell; a wire connected with and leading from said contact spring, a resilient open-ended channel-shaped clip of a length commensurate with the length of said cylinder and attached to and in substantial parallelism with one side of said cylinder, an elongated miniature bulb fitted removably in the intermediate portion of said clip, said bulb having an internal filament, caps closing the opposite ends of the bulb and electrically connected with adjacent end portions of said filament, said caps having concaved retention seats, a current conducting fixture having an insulated body removably fitted in one end portion of said clip, said body having a current conducting contact head, said contact head being convex and removably coacting with the adjacent concaved seat on the adjacent cap of said bulb, said wire being connected with said body and also with said contact head, a second contact fixture including a cylindrical cup of insulation material, said cup being removably fitted into said clip at the opposite end of the clip, a spring-pressed plunger slideable in said cup, said plunger having a convex contact head fitting removably in the seat provided therefor in the adjacent cap, and a second wire affording electrical circuit connection between the adjacent end of said dry cell and said second-named contact head.
